COMBINED TRAIN ORDER AND TRAFFIC SIGNAL

Filed June 19, 1925

FIG. 1.

FIG. 2.

INVENTOR.
J. Bennett,
Neil H. Preston,
his ATTORNEY

UNITED STATES PATENT OFFICE

JERRY BENNETT, OF SCOTTSVILLE, NEW YORK, ASSIGNEE TO GENERAL RAILWAY SIGNAL COMPANY, OF ROCHESTER, NEW YORK

COMBINED TRAIN ORDER AND TRAFFIC SIGNAL

Application filed June 19, 1925. Serial No. 38,243.

This invention relates to semi-automatic signals for railways, and more particularly to a multiple aspect signal which by the number of distinctive indications available may 5 be used to give the usual indications of traffic conditions ahead automatically and further by reason of superimposed manual control give other information which is not likely to be mistaken for an indication of favorable 10 traffic conditions ahead.

In the operation of trains on most of the railways, train orders are at times required to instruct the train crew as to how they shall reach their destination and where they shall 15 meet certain other trains or shall allow other trains to pass them from the rear. These train orders have generally been transmitted from the train dispatcher to the train crew in two different ways depending on the nature 20 and importance of the train order. When the train order is such as to seriously endanger the train if it is not carried out, the train is required to stop to take the order in which event the engineer or conductor is required 25 to sign an acknowledgement that he has received such order; whereas if the order is such as to facilitate traffic rather than to safeguard it, the order may be given to the train crew without requiring them to stop to 30 sign such receipt, and in which event the order is tied to a hoop, or the like, which is handed to a train man on a passing train. In transmitting train orders in this way it is, of course, necessary to inform the train crew 35 properly as to when and how a train order is to be transmitted to them, and in the past a three-position signal has in some instances been used for this purpose. On account of the limited number of clearly distinguishable 40 colors available, train order signals have in many instances employed the same color indication as the usual automatic signals, namely, green, yellow and red, and even if color distinction were employed to distinguish 45 train order signals from automatic signals confusion might easily result in mistaking a train order signal for an automatic signal on account of the limited number of 50 clearly distinguishable colors. In any event

it has happened that a train order signal has been mistaken as a proceed automatic or semi-automatic signals as a result of which a wreck has occurred.

With the above and other important considerations in mind, it is proposed in accordance with the present invention to employ a signal which has a sufficient number of distinctive combination color aspects, so that conditions of traffic ahead as well as information as to the transmission of train orders can be given by the same signal, as a result of which there cannot be a confusion between the usual automatic and a train order signal. As a further object of the present invention it is proposed 60 to display a caution signal at the next signal location in the rear of such combined train order and traffic signal under traffic conditions which require the display of such caution signal and also when the train is required 65 to come to a stop to take a train order.

More specifically, it is proposed to provide a three-condition light signal for the purpose of indicating conditions of traffic ahead, employ a two-condition light signal having a 70 predetermined spaced relation to the automatic signal for the purpose of indicating that a train order is to be transmitted to the train crew, and in employing a single aspect light signal having a different fixed relation 75 to the automatic signal so that the train crew must either read the automatic signal in connection with the single aspect signal or must read this automatic signal in connection with the train order signal before a complete and eligible signal indication can be accepted by 80 the train crew.

Other objects of the invention reside in the provision of means for superimposing manual control upon the automatic control of the signal from a remote point, preferably including a desk type circuit controller together with indicators which tell the operator if the necessary number of lamps are burning to give 85 the indication which has been set up.

Other objects, purposes and characteristic features of the invention will appear from the following description and the drawings.

In describing the invention in detail refer- 100

ence will be made to the accompanying drawings in which:—

Fig. 1 diagrammatically illustrates a signal location in automatic signal territory at which a semi-automatic signal embodying the present invention is located; and

Fig. 2 shows a front view of the combined train order and automatic signal and also shows a chart indicating the seven different aspects which are used in the particular arrangement in which the invention has been illustrated.

Referring to the drawings, the particular embodiment of the invention illustrated shows color light signals for carrying out the multiplicity of aspects for giving both conditions of traffic ahead and information as to the transmission of train orders although position light signals or semaphore signals alone, or in combination with one or more light signals, may be employed instead of the particular arrangement illustrated.

Each of the light signal units shown consists of a closed compartment having darkened walls and an opening and preferably containing a lens therein, which is capable of converging a large spherical angle of light from a concentrated light source, such as the filament of an incandescent lamp, into a rather narrow beam having a color the same as that of the lens. This construction avoids the reflection of light from the outside and thereby avoids a false or phantom indication, and at the same time constitutes an efficient light projecting unit. Also the incandescent lamps used in connection with these light signals each preferably have a concentrated filament which is located in the focus of such lens.

Referring to Fig. 1, a portion of the track of a railway system is shown, in which the normal direction of traffic is as indicated by the arrow, which track has its rails 1 divided into blocks by insulating joints 2 of which the adjacent ends of the blocks H and I only have been shown. At the exit end of the block I there is provided a source of alternating current potential (not shown) the instantaneous polarity of which depends on traffic conditions in the next block in advance of the block I, so that the track relay T connected across the rails at the entrance end of the block I is energized to its normal position, in which it has been shown, if both the blocks I and the block next in advance thereof are unoccupied. This relay assumes the reverse dotted position when the block in advance of the block I is occupied and assumes the pendant de-energized position if the block I is occupied by a train which shunts the track phase winding of this relay T. This relay T also has a line phase winding 8 which winding is connected directly across one secondary winding 9 of the track transformer 10, which

transformer receives its energy from line transformer 11.

In the preferred embodiment of the invention illustrated the three-condition color light signal comprises a clear lamp 15 preferably colored green, a caution lamp 16 preferably colored yellow, and a danger lamp 17 preferably colored red located on one side of the signal pole 18, the two aspect train order signal includes a lamp 19 preferably colored yellow and the lamp 20 preferably colored red, and the marker light comprises a red lamp 21 located a considerable distance below the train order signal. Each of the lamps just mentioned is connected in a separate circuit to the secondary winding of its individual transformer, which transformers have for convenience been numbered 24, 25, 26, 27, 28 and 29. These various signal lamps may be controlled in any suitable manner, but preferably are controlled jointly by the track relay T and the desk circuit controller DC which is preferably one of the type more specifically described in the application of R. C. Leake, Ser. No. 602,042, filed November 20, 1922.

This desk circuit controller includes a handle 30 which may, if desired, be locked in any suitable way as by mechanical interlocking mechanism or by an electric lock, and through the medium of which certain circuits may be opened and closed as conditions require. This desk circuit controller also includes indicators A, S and AS, which signify that no train order is to be given to the train crew, that the train is to stop to receive a train order and that the train is to receive a train order at speed, respectively. The apparatus illustrated also includes a repeater relay RR which is preferably slow-acting so that it does not assume its de-energized condition when traffic conditions change from clear to caution, during which change this relay RR is momentarily de-energized. In other words, if this relay RR were not slow-acting a momentary indication of danger traffic conditions ahead would be given when the track relay T changes from its normal to its reversed position, which momentary indication might cause confusion or might cause the train crew to place less reliance upon the signal indication; as constructed, however, this relay RR, does not assume its de-energized position during reversal of the relay T.

The main winding of this repeater relay RR, as readily appears from the drawings, is energized through the contact 33 of the track relay T when this track relay is either energized normal or reverse, and the auxiliary winding 34 of this repeater relay RR is energized whenever the handle 30 of the desk circuit controller DC is in either of its extreme positions, through the medium of contacts 35 and 36 of this circuit controller, so

that the repeater relay RR is de-energized when either the track relay T is de-energized or the circuit controller DC is in its neutral position. From the circuit for the main winding of the relay RR it is obvious that this relay RR is de-energized when the block I is occupied, and for this reason the pole changing contacts 37 and 38 of this repeater relay RR change the relative polarity of the alternating current derived from the secondary winding 32 and applied to the track circuit of the block H. From the circuit for its auxiliary winding 34 it appears that relay RR is de-energized when the controller handle 30 is in its neutral stepping position; so that the net result is the signal located at the entrance of the block H will indicate caution whenever this relay RR is de-energized, either because a stop train order signal has been set up manually or because caution traffic conditions exist by reasons of the presence of a train ahead in block I.

It readily appears that the transformers 28 and 29 which feed the green lamp 15 and the caution lamp 16 of the automatic signal are energized when the track relay T is energized normal and reverse, respectively; and that these transformers receive their energy through the front contact 39 of the relay RR, and the contact 41 of the relay T, so that if this relay RR is de-energized neither of the lamps 15 or 16 can be energized. Further, if the relay RR is de-energized, the contact 40 of this relay RR applies energy to the primary winding of the transformer 25 so as to energize the red lamp 17 of the automatic signal. The other side of the primary windings of these transformers 25, 28 and 29 are connected to a common wire C, which is connected to one side of the primary winding 44 of the transformer 10. Further, it should be noted that the current which may be applied to any one of the lamps 15, 16 or 17 of the automatic signal, through contacts 39, 40 and 41, is derived from a common feed wire F, which is connected to the transformer 11 through contact 47 of the desk circuit controller DC, one of the indicators A, S or AS depending on the position of the desk circuit controller DC, and the wires 46 and 48; so that regardless of the positions of the relays T and RR or the position of desk circuit controller handle 30 only one of these lamps 15, 16 or 17 can be lighted and the current flowing through the primary winding of its transformer flows through one of the indicators A, S or AS.

It may be pointed out at this time, that this current, just mentioned, is not sufficient to energize these indicators to an extent to give an indication, these indicators being designed so as to assume their energized indicating positions only if the current flowing in the primary windings of two of the transformers flows through such indicator and providing

that the secondary winding of these transformers are connected to lamps which have their filaments intact.

As thus far described it is apparent that the automatic signal will indicate conditions of traffic ahead so long as the desk circuit controller DC is in either of its extreme positions but that the red lamp 17 will be energized and the lamps 15 and 16 will be de-energized irrespective of traffic conditions ahead if the desk circuit controller DC is in its neutral position.

Let us now consider the functions of the contact 50 of the desk circuit controller DC which contact determines the character of train order information to be given to an approaching train. This contact 50 through wires 51 and 52 is connected to one side of the secondary winding of the transformers 24, 27 and 26 when the desk circuit controller DC is in its normal, its reverse and its neutral position respectively. The other side of this primary winding of these transformers also being connected through the medium of wire 55 to the common feed wire F, which feedwire F receives its current through the contact 47 of the desk circuit controller DC and one of the indicators A, S or AS as the case may be through wires 46 and 48 connected to the other side of the secondary winding of the transformer 11.

From these circuits it readily appears that the red marker lamp 21 is energized when the desk circuit controller DC is in its normal position; the yellow lamp 19 is energized when this circuit controller is in its reverse position; and the red lamp 20 is energized when the controller is in its neutral position. Considering now the flow of current to one of the transformers 24, 26 and 27 through the medium of contact 50 of the desk circuit controller, and the flow of current to the primary winding of one of the transformers 25, 28 and 29 through the medium of contacts 39, 40 and 41 and that the currents for any two transformers which may be energized at the same time, for reasons just given, is derived from the feed wire F through one of the indicators A, S or AS depending on the position of handle 30; it appears that such indicator will assume its indicating position and inform the operator that there are two lamps illuminated and that the engineer of the approaching train has the necessary information only if the filaments of the lamps energized by these two transformers are intact.

Referring to Fig. 2 let us now consider the number of distinctive indications that can be given by the combined train order and automatic signal embodying the present invention, which indications have been graphically illustrated in Fig. 2 and for convenience have been numbered 1 to 7, inclusive. With the desk circuit controller in

its normal position the red lamp 21 is energized regardless of the condition of the automatic signal comprising lamps 15, 16 and 17, from which it is obvious that (1) under clear traffic conditions of the block I and the next block in advance thereof (not shown) the green lamp 15 and this red lamp 21 are energized, which signifies proceed; (2) with the block to the right of the block I occupied, under which condition the polarity of the track circuit current in the block I is reversed, and the track relay T is energized to the reverse position, the yellow lamp 16 is energized in combination with the red lamp 21, which signifies caution; and (3) if the block I is occupied and the track relay T is de-energized it causes de-energization of the repeater relay RR by reason of dropping of contact 33 which in turn will 20 energize the red lamp 17 of the automatic signal together with the red lamp 21 which signifies danger. During each of the three indications of proceed, caution and danger, just mentioned, the indicator A assumes its 25 indicating position and indicates that the automatic signal together with its red marker lamp 21 is functioning properly.

If now, the operator wishes to transmit a train order to the train crew without requiring the train to come to a stop he will move the handle 30 to the extreme right-hand position and in so doing will by contact 47 select the at-speed indicator AS, and will by contact 50 extinguish the red lamp 21 35 and illuminate the yellow lamp 19. Under this condition the three indications marked 4, 5 and 6 in the diagram in Fig. 2 will result. The automatic signal comprising lamp 15, 16 and 17 will function in exactly 40 the same manner as it does in the first three indications, (1), (2) and (3) just mentioned, so that it is not necessary to discuss these three indications specifically.

If the train crew is to come to a stop to take 45 a train order and sign a receipt therefor the operator will move the desk circuit controller to the neutral position and in so doing will illuminate the red lamp 20 through the medium of contact 50 and will effect de-energization of the relay RR through the medium 50 of contacts 35 and 36. With the relay RR de-energized the automatic signal can indicate danger only, that is, the red lamp 17 is energized just the same as if the block I were 55 occupied; so that two red lamps arranged horizontally are lighted to inform the engineer of the approaching train that he is to stop to take a train order. If these two red lamps 17 and 20 are properly energized the 60 stop indicator S will assume its indicating position and inform the operator accordingly, also, with the relay RR de-energized to give the "stop train order signal" the next signal in the rear will indicate caution.

65 It is considered expedient to briefly men-

tion, as follows, what each of the indications tabulated in Fig. 2 is intended to convey to the engineer in the particular embodiment of the invention illustrated:—(1) proceed; (2) caution; (3) danger; (4) take train order without stopping and then proceed; (5) take train order without stopping and then proceed with caution; (6) take train order without stopping and then proceed at low speed; and (7) stop for train order.

In those systems in which the rules require the train to be brought to a stop before an automatic stop signal is passed the last two indications would be interpreted as follows:—(6) stop for train order and proceed at low speed; (7) stop and sign for train order.

In order to assure full safety to an approaching train in a system employing a signal embodying the present invention the operator will be required to keep close watch 85 that the proper indicator A, S or AS is indicating, at all times, and in order to aid the operator it may be desirable to add an audible signal which sounds whenever none of these indicators is in an indicating position. 90 This precaution should be taken, since the engineer might mistake the illumination of a single lamp for that of an ordinary automatic signal, or if all of the lamps are extinguished may not note the fact that he has 95 passed a signal location. With the provision of these indicators the operator will be properly informed and may, if necessary, flag the train in any other suitable way.

Having thus shown and described one specific embodiment of the present invention, it is desired to be understood that the present invention is not limited to the employment of color light signals, but may if desired be carried out by the employment of position 105 light signals or semaphore signals alone, or in combination with color light signals, and that various changes, modifications and additions may be made to adapt the invention to the particular type of railway signaling 110 system in connection with which it is to be used without departing from the scope of the invention or the idea of means underlying the same.

What it is desired to be secured by Letters 115 Patent is:—

1. A combined train order and traffic signal comprising, a plurality of distinctive color light signals, and means for lighting pairs of lamps in said signals substantially vertically disposed to indicate distinctively various conditions of traffic ahead, and pairs of lamps in said signals substantially horizontally disposed to indicate distinctively any one of a plurality of train order informations.

2. A combined train order and traffic signal comprising, a plurality of distinctive color light signals, and means for lighting pairs of lamps in said signals substantially

vertically disposed to indicate distinctively various conditions of traffic ahead and pairs of lamps in said signals substantially horizontally positioned to both distinctively indicate conditions of traffic ahead and visually transmit certain train order information.

3. In a combined signal for railway signaling purposes, the combination of signaling means for indicating clear, caution and danger traffic conditions ahead and for causing the next signal in the rear of said signaling means to indicate caution when said signaling means indicates danger, supplemental signaling means located at the signal location of said signaling means and means for energizing the supplemental signaling means and at the same time causing said signal in the rear to indicate caution.

4. In a combined automatic and manual signal for railway signaling, the combination of signaling apparatus for giving a plurality of signal indications each indication of which is effected by illuminating a plurality of incandescent lamps, automatic means for controlling said signal apparatus, and indicating means for indicating whether or not the required number of lamps for giving a particular signal indication are illuminated.

5. Semi-automatic multiple aspect signal comprising, a three condition automatic traffic indicating signal, a multiple aspect train order signal located adjacent said three condition signal, a marker light, and means to illuminate the marker light only, and cause it to be read in connection, with said three condition signal, when said train order signal is in its non-indicating condition.

6. A combined train order and traffic signal comprising, a plurality of manually and automatically controlled color light signals, and means for lighting pairs of lamps in said signals substantially vertically disposed to indicate distinctively various conditions of traffic ahead, and pairs of lamps in said signals substantially horizontally disposed to indicate distinctively any one of a plurality of train order informations.

7. A combined train order and traffic signal comprising, a plurality of distinctive color light signals, including traffic controlled signals, and means for lighting pairs of lamps in said signals substantially vertically disposed to indicate distinctively various conditions of traffic ahead and pairs of lamps in said signals substantially horizontally positioned to both distinctively indicate conditions of traffic ahead and visually transmit certain train order information.

8. In a signal system, a plurality of traffic controlled light signals, a plurality of other light signals, and indicating means placed in indicating condition only if a plurality of the light signals is lighted.

9. In a signal system, a plurality of

traffic controlled light signals, a plurality of other light signals, and indicating means assuming indicating condition only during lighting of one of the traffic controlled signals and one of the said other signals.

10. In a combined traffic and train order signal system, traffic controlled light signals manually controlled train order light signals, and means for indicating when one traffic controlled signal and one train order signal is simultaneously lighted.

11. In a combined traffic and train order signal system, traffic controlled light signals, manually controlled train order light signals, and indicating means connected to be responsive only to the combined energizing currents for one of the traffic controlled signals and one of the said other signals.

12. In a signal system, clear, caution and danger signals controlled by traffic conditions train-order signals indicating a train order, at stop, at speed, and no order, manual means for energizing the train order signals, and connections whereby energization of the "at stop" train order signal, energizes the traffic danger signal regardless of traffic conditions.

13. In a signal system, clear, caution and danger signals controlled by traffic conditions, train-order signals indicating a train order, at stop, at speed, and no order, manual means for energizing the train order signals, and an indicator responsive only while one of the traffic signals and one of the train-order signals is simultaneously energized.

14. In a signal system, a plurality of traffic controlled signals, a plurality of manually controlled train-order signals, and means for causing simultaneous energization of one of each class of signals.

15. In a signal system, a plurality of traffic controlled signals, a plurality of manually controlled train-order signals, means for causing simultaneous energization of one signal of each class, and indicating means assuming indicating condition only when one signal of each class is energized.

In testimony whereof I hereby affix my signature.

JERRY BENNETT.
